UNITED STATES PATENT OFFICE.

RALPH ALLEN, OF SHELTON, CONNECTICUT, ASSIGNOR TO THE ACME TOOL & MACHINE CO., OF DERBY, CONNECTICUT, A CORPORATION.

CARPENTER'S PLANE.

1,324,486.

Specification of Letters Patent.

Patented Dec. 9, 1919.

Application filed July 10, 1919. Serial No. 309,796.

To all whom it may concern:

Be it known that I, RALPH ALLEN, a citizen of the United States, residing at Shelton, in the county of Fairfield and State 5 of Connecticut, have invented a new and useful Improvement in Carpenters' Planes; and I do hereby declare the following, when taken in connection with the accompanying drawings and the characters of reference 10 marked thereon, to be a full, clear, and exact description of the same, and which said drawings constitute part of this application, and represent, in—

Figure 1 a view partly in side elevation 15 and partly in vertical, central section, of a carpenter's plane constructed in accordance with my invention.

Fig. 2 a plan view thereof with a portion of the cutter-clamp broken away.

Fig. 3 a detached reverse plan view of the cutter-clamp.

Fig. 4 a detached view in side elevation of the cutter-clamp lever.

My invention relates to an improvement 25 in carpenters' planes, and more particularly to the means employed for clamping their cutters in place, the object being to provide a simple, reliable and convenient device for the purpose specified.

With these ends in view, my invention 30 consists in a carpenter's plane having certain details of construction as will be hereinafter described and pointed out in the claims.

In carrying out my invention as herein shown, I form a cam-like, transversely arranged pivot-bearing 2 of eccentric cross-section upon the upturned rear end 3 of the web 4 of a one-piece cutter-clamp which also comprises a hood-like handle 5 located at 40 its rear end, a gripping-plate 6 located at its forward end and parallel side flanges 7 which connect the said handle and plate. As shown, the cam-like pivot-bearing 2 is located between two corresponding shoulders 8 made integral with it and with the rear edge of the web 4.

Upon the pivot-bearing 2 I mount a one-piece hook-shaped cutter-clamp lever comprising a forwardly extending finger-piece 50 9, a mounting-loop or bow 10, and a depending, forwardly bent pressure-foot 11, the said mounting-loop inclosing a cam-surface 12 which co-acts with the pivot-bearing 2 aforesaid. As shown the lever is strengthened by an integral rib 13.

By constructing the cutter-clamp and the cutter-clamp lever as described, I provide for pivotally mounting the lever directly upon the rear end of the web of the clamp and within the handle thereof without resorting 60 to an independent pivot for the purpose, and utilize the bearing 2 as a cam for springing the clamp. On account of its hook-like form and its protected location within the hood-like handle of the clamp, the lever 65 will not in any ordinary use of the plane become dislodged.

Otherwise than as described, the plane is of standard construction. A screw 14 passing downward through the key-slot 15 70 in the web 4 into the body 16 of the plane holds the clamp in place upon the body, which is formed with supports 17 and 18 for the cutter 19, which is longitudinally adjusted in the usual manner by a screw 20. 75 At its forward end, the plane is provided with an adjustable mouth-piece 21 locked in place by a nut 22.

When the finger-piece of the lever is 80 forced downward into the position in which it is shown by Figs. 1 and 2, its pressure-foot 11 presses down upon the upper surface of the cutter 19 with enough force to spring the cutter-clamp sufficiently to cause its gripping-plate 6 to grip the cutter by its 85 forward end and rigidly hold it in place, this springing of the clamp being effected by the cam-like pivot-bearing 2 in conjunction with the cam-surface 12 of the lever. By lifting the finger-piece 9 of the clamp-lever into the position in which it is shown 90 by broken lines in Fig. 1, the pressure upon the cutter is released and the same may then be adjusted as required.

I claim:—

1. In a carpenter's plane, the combination with the body and cutter thereof, of a one-piece cutter-clamp having a transversely arranged bearing of eccentric cross-section; and a hook-shaped cutter-clamp lever mounted upon the said bearing and adapted when rocked thereupon to press down upon the cutter and spring the clamp for holding the cutter in place. 100

2. In a carpenter's plane, the combination with the body and cutter thereof, of a one-piece cutter-clamp comprising a handle located at its rear end, a web, a gripping-plate at the forward end of the said web, and a transversely arranged bearing formed 105 110

upon the rear edge of the said web and eccentric in cross-section; and a hook-shaped cutter-clamp lever comprising a forwardly extending finger-piece, a mounting-bend or 5 loop interiorly shaped to form a cam, and a pressure-foot, the said lever being mounted upon the said bearing and operating when rocked thereupon to press down upon the cutter and so spring the clamp and cause

the same to grip the cutter at the forward 10 end thereof.

In testimony whereof, I have signed this specification in the presence of two subscribing witnesses.

RALPH ALLEN.
